UNITED STATES PATENT OFFICE.

PETER STEINHAUER, OF ST. LOUIS, MISSOURI.

DIFFERENTIAL GEAR.

No. 876,501.

Specification of Letters Patent.

Patented Jan. 14, 1908.

Application filed July 15, 1907. Serial No. 383,823.

To all whom it may concern:

Be it known that I, PETER STEINHAUER, citizen of the United States, residing at St. Louis, State of Missouri, have invented certain new and useful Improvements in Differential Gears, of which the following is a full, clear, and exact description, reference being had to the accompanying drawings, forming a part hereof.

10 My invention has relation to improvements in differential gear for self-propelled vehicles or automobiles; and it consists in the novel construction and arrangement of parts more fully set forth in the specification and 15 pointed out in the claims.

In the drawings, Figure 1 is a longitudinal middle section taken through the gearing, the shaft being in elevation; Fig. 2 is a vertical transverse section on the line 2—2 of Fig. 20 1; Fig. 3 is a vertical transverse section on line 3—3 of Fig. 1, a part of the wall of the inner plate or disk being broken away; and Fig. 4 is an inner face view in perspective of the 25 plate carrying the pinions.

25 The object of my invention is to provide self-propelled vehicles with a differential gear which will carefully and accurately adjust the velocity of the wheels to the actual distance traveled thereby when turning a corner 30 or when the travel of the vehicle is deflected from a direct or straight course. In such event no slipping of the inside wheel can take place, and steering of the vehicle can be controlled to a nicety and with precision; besides 35 no lost motion can be sustained by either wheel.

In detail the invention may be described as follows:

Referring to the drawings, S, represents 40 the shaft of either the front or rear trucks on the ends of which the wheels W, W', are loosely mounted, the hub II, II', of each wheel being of prevailing construction. Passed loosely over the shaft is a sleeve 1, to 45 which rotation is imparted by the sprocket wheel 2 keyed thereto, and driven from any source of power (not shown). Referring to the right of Fig. 1, the sleeve has keyed thereto a disk 3 along whose inner face are disposed 50 a series of pinions 4 revolving about pins or studs 5 whose opposite polygonal or square ends are carried respectively by the disk 3 and by an annular ring 6, the latter being secured at intervals to the ribs 7 cast with the

disk 3, and bolted or screwed to the latter, 55 the securing screws 8 being passed through the ring and through the screw-threaded sockets 9 formed at the middle of each rib 7. Keyed to the shaft S adjacent to the disk 3, and between the latter and the wheel W is a 60 gear wheel 10 with the teeth of which the pinions 4 mesh; and carried by the wheel is a plate or member 11 having a marginal interiorly toothed flange or rim 12 spanning and engaging the pinions 4, and overlapping the 65 edge of the disk 3.

Referring to the left-hand wheel W', the said wheel has secured thereto a similar member or plate 11' having an interiorly toothed flange or rim 12', the teeth of the 70 latter meshing with the pinions 4' disposed along the inner face of a disk 3' likewise keyed to the sleeve 1, the studs 5' of the pinions having their ends carried respectively by said disk 3' and by the annular ring 6' secured at intervals to the ribs 7' cast with the disk 3' and bolted or screwed to the latter, the securing screws 8' being passed through the ring and through the screw-threaded sockets 9' formed at the middle of each rib 7'. 75 Keyed to the shaft S adjacent to the disk 3', and between the latter and the wheel W' is a gear wheel 10' with the teeth of which mesh the pinions 4'', the latter likewise meshing with the pinions 4' and being mounted on 80 studs 5'' carried by the disk 3' and ring 6' respectively. The pinions 4', 4'' are not disposed in the same radial line from the axis of the shaft, their centers of rotation being on 85 distinct radial lines diverging from a common 90 center (axis of the shaft S) and being at different radial distances from such center (Fig. 2). The purpose of this arrangement is to preserve as nearly as possible an equality or 95 the same relation in the diameters between said pinions and gear wheel 10' as exists between the pinions 4 and gear wheel 10, thereby reducing the friction between the intermeshing gears, and at the same time to secure simultaneous contrary rotations at 100 equal speeds for the wheels W, and W' when the shaft S is deflected to permit the vehicle to turn from a direct line of travel. This 105 equality in the speeds between the parts referred to of course flows from the fact that the gears 10, and 10' and disks 3, 3' are respectively secured to the shafts and to the sleeve 1, it being obvious that any given ve-

lacity imparted to the shaft at one end as a result of any acceleration of the wheel at that end, will be imparted to the shaft at the opposite end, a corresponding velocity being 5 imparted to the wheel at such opposite end in the opposite direction.

The operation of the device may be described as follows: Motion being imparted to the sleeve 1 in a direction corresponding to 10 that of the hands of a watch with reference to the wheel W in Fig. 3, and the vehicle traveling in a straight or a direct line, it follows that as the disk 3 is keyed to the sleeve and the pinions 4 thereof are in simultaneous mesh 15 with the gear 10 and the interiorly toothed flange 12, and are virtually locked against independent rotation about their own axes, they will simply carry the parts 10 and 12 bodily with them as the disk 3 revolves, and 20 thus revolve the gear 10 and wheel W in the same direction. This means that the shaft S will revolve in the direction of the hands of a watch. Assuming this to be the case, and looking now at Fig. 2, the sleeve 1 and shaft S 25 having the corresponding parts 3' and 10' keyed respectively thereto, and the pinions 4', 4'' interlocked with the teeth of the flange 12' and the gear 10', it follows that the rotation of the parts on this end will correspond 30 in direction with the corresponding parts on the opposite end of the shaft, and both wheels W, W', will rotate in the same direction and at the same rate of speed. Suppose however, that the chauffeur or driver deflects the 35 shaft in a direction so as to steer the vehicle around a corner, and that the wheel W happens (by way of example) to be the outside wheel which is obliged to swing around the outer circle of the vehicle's travel. This sudden deflection of the shaft imparts an independent motion of rotation to the wheel W in excess of that which it possessed when the vehicle traveled in a direct line. This excess 40 in the rotation causes the wheel to gain on the angular velocity of the disk 3 keyed to the sleeve, and as to this excess the disk becomes for practical purposes stationary; and under the circumstances and by virtue of the thus accelerated velocity of the wheel, the 45 gear 12 will impart a rotation to the pinions 4 about their axes as shown by the arrows in Fig. 3, this rotation tending to retard the rotation of the shaft S, being that the pinions in such rotation tend to impel the gear 10 and 50 shaft S to which it is keyed in the opposite direction (see arrow Fig. 3). This retarding influence on the shaft's rotation is of course communicated to the opposite end thereof where it has the following effect: The shaft 55 tending now to revolve contrary to the hands of a watch, the gear 10' keyed thereto will revolve with it; the gear 10' tends to impart a direction to the pinions 4'' with the hands of a watch; the pinions 4'' will tend to drive the 60 pinions 4' contrary to this direction, and the 65

pinions 4' will tend to rotate the gear 12' and hence the wheel W' to which it is secured likewise contrary to the direction of the hands of a watch, and therefore contrary to the direction of the wheel W. As the wheel 70 W' is the inside wheel, and has accordingly the least distance to travel in turning a corner, its degree and direction of rotation are thus controlled according to the purpose it is to subserve. If on the other hand we let the 75 wheel W' be the outside wheel, a similar result would affect the wheel W which would then become the inside wheel. That is to say, an acceleration of the wheel W' would tend to accelerate the rotation of the gear 80 10', this acceleration being imparted to the gear 10 keyed to the shaft S at the opposite end; but an acceleration of the shaft S in the same direction would, owing to the interposition of but a single pinion 4 between 85 the gear 10 and 12, tend to revolve the gear 12 in the opposite direction, and hence the wheel W to which said gear 12 was secured.

The above differential gear is extremely sensitive, and the wheels only run at the 90 same velocity and in the same direction when the vehicle is traveling in a straight or direct line. The moment the shaft is deflected to turn a corner, or to the right or left of such a direct line, the wheel which is to become the inside wheel is immediately affected in the manner indicated; that is to say, its motion is retarded and in some cases may even be reversed, since such reversal would be but natural considering that for a sweeping deflection of the shaft the opposite ends of the latter virtually oscillate simultaneously in opposite directions. I may of course avail myself of any equivalent constructions of the details here shown, and may 95 in a measure depart therefrom without in any wise effecting the nature or spirit of my invention. 100

Having described my invention, what I claim is:

1. A differential gear for vehicles comprising a shaft, wheels loosely mounted at the opposite ends thereof a rotatable member encompassing the shaft between the wheels, an inner toothed gear carried by each wheel, a gear wheel secured to the shaft adjacent to each wheel, a series of pinions rotatable about their axes carried by the rotatable member adjacent to one of the wheels and meshing with the gear wheel on the shaft and with 115 the gear on the wheel, a series of pinions rotatable about their axes carried by the rotatable member adjacent to the opposite wheel and meshing with the gear wheel, a second series of rotating pinions likewise carried by 120 the rotatable member adjacent to said opposite wheel, said second series being disposed to one side of the first series and along radial lines concentric with the radial lines of disposition of the first series but at a different dis- 125 130

tance from the common center of said radial lines, said second series meshing with the first series of pinions and with the adjacent gear wheel secured to the shaft, substantially as 5 set forth.

2. A differential gear for vehicles comprising a shaft, wheels loosely mounted at the opposite ends thereof, a rotatable member encompassing the shaft between the wheels, 10 an inner-toothed gear carried by each wheel, a gear wheel secured to the shaft adjacent to each wheel, a series of rotatable pinions carried by the rotatable member adjacent to one of the 15 wheels and meshing with the gear wheel on the shaft and with the gear on the wheel, two series of rotatable pinions disposed along radii diverging from a common center on the axis of rotation of the shaft, carried by the rotatable member adjacent to the opposite wheel and respectively meshing the one series with the other, and with the gear 20 wheel on the shaft and with the gear wheel on the shaft, the parts operating substantially as set forth.
- 25 3. A differential gear for vehicles comprising a shaft, wheels loosely mounted at the opposite ends thereof, a rotatable sleeve encompassing the shaft between the wheels, an inner-toothed gear carried by each wheel, a 30 gear wheel secured to the shaft adjacent to each wheel, a series of rotatable pinions carried by the sleeve adjacent to one of the

wheels and meshing with the gear wheel on the shaft and with the gear wheel on the wheel, two series of rotatable pinions disposed along radii diverging from a common center on the axis of rotation of the shaft, carried by the sleeve adjacent the opposite wheel and respectively meshing, the one series with the other, and with the gear 35 wheel on the shaft and with the gear wheel on the wheel, the parts operating substantially as set forth.

4. A differential gear for vehicles comprising a shaft, wheels loosely mounted thereon, and means for imparting rotation to the wheels in reverse directions by a deflection of the shaft from a position corresponding to the travel of the vehicle in a direct line, substantially as set forth.

45 5. A differential gear for vehicles comprising a shaft, wheels loosely mounted thereon, and gearing connected to the wheels for imparting thereto respectively rotation in reverse directions by a deflection of the shaft 50 from a position corresponding to the travel of the vehicle in a direct line, substantially as set forth.

In testimony whereof I affix my signature, in presence of two witnesses.
